UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN.

COMPOSITE BEARING FOR WROUGHT-METAL STRUCTURES AND METHOD OF FORMING THE SAME.

1,217,633.

Specification of Letters Patent. Patented Feb. 27, 1917.

Application filed March 31, 1916. Serial No. 87,952.

To all whom it may concern:

Be it known that I, ALDEN L. PUTNAM, a citizen of the United States of America, residing at Detroit, in the county of Wayne 5 and State of Michigan, have invented certain new and useful Improvements in Composite Bearings for Wrought-Metal Structures and Methods of Forming the Same, of which the following is a specification, reference being had therein to the accompanying drawings.

The invention relates to wrought or pressed metal structures designed for use as working parts and having bearing faces in 15 contact with relatively movable members. It is the object of the invention to obtain a more durable working surface, avoiding necessity of mechanically attaching bushings or bearing plates and maintaining the 20 strength and lightness of the structure.

In the present state of the art many machine elements usually formed from cast metal may be lighter and stronger if formed from pressed or wrought metal. Where, 25 however, these elements have working surfaces or bearings, it has been found that the wrought metal is not as well adapted for this purpose as cast metal. In particular cast iron is a much more durable working 30 surface than wrought iron or steel, particularly where the coöperating member is formed of hardened steel. Thus it has been the practice heretofore where working members are formed of wrought metal to provide 35 bushings or working surfaces of cast iron or some equally good wearing material. It is necessary, however, to make these bushings or wearing surfaces of sufficient thickness to possess the required mechanical 40 strength, and as a consequence the size and weight of the structure is increased, so that the advantages due to the wrought metal construction are to a large extent lost. With 45 my improvement I have overcome this defect by molecularly uniting or integrating with a wrought metal structure a wearing surface of a metal of different character. Specifically my improvement comprises the fusing on to the surface of a structure of 50 pressed iron or steel a facing of cast iron.

In the drawings:

Figure 1 is a diagrammatic elevation illus-

trating the manner of re-facing a wrought metal structure;

Fig. 2 is a cross-section showing a pressed 51 sheet-metal journal bearing interiorly re-faced; and

Fig. 3 is a cross-section thereof.

In carrying out my invention the wrought metal structure is first fashioned either by 60 pressing, drop-forging or in any other suitable way. As shown in Fig. 2, A is a portion of the cylindrical wall of a sheet-metal piston, and B is an inturned sleeve bearing for engaging the wrist-pin of the connecting rod. Where this member is formed of pressed sheet-metal and is used in connection with a hardened steel wrist-pin a poor wearing surface is produced and it is difficult to prevent seizing and cutting of the metal. 70 By making the sleeve B large and engaging a cast iron bushing therewith the difficulty of wearing surface is overcome but the increased size and thickness of the parts is 75 objectionable. I have therefore solved the difficulty by flowing molten cast iron over the inner surface of the sleeve under sufficient heat to fuse and integrate said metal with the steel surface and to produce a thin 80 cast-iron lining, as indicated at C. The oxy-acetylene blow torch, as indicated at D Fig. 1, or by any other source of intense heat. The cast metal may be supplied from a bar E, and when fused and highly heated 85 will integrate with the steel surface. Any suitable flux may be used, such for instance as borax.

I have found that an exceedingly thin coating of the cast metal is all that is required to form a good wearing surface, so that the completed structure is but very slightly increased in weight or in size. Preferably the pressed metal structure is first bored or machined to a size slightly greater 95 than that of the finished bearing, and then this surface is re-faced as has been described and finally finished to size.

What I claim as my invention is:—

1. The combination with a wrought metal 100 structure having a portion thereof forming a working bearing, of a facing for said bearing of relatively high-fusing cast metal molecularly integrated therewith.

2. The combination with a wrought metal structure having a portion thereof forming a working bearing, of a facing for said bearing formed of cast iron fused thereon and 5 molecularly integrated therewith.
3. The combination with a pressed sheet-metal structure having a portion thereof forming a working bearing, of a facing for said bearing formed of cast iron fused there- 10 on and molecularly integrated therewith.
4. The method of forming composite bear- 15 ings comprising the pressing of sheet iron or steel to the form required, machining the surface and coating the machined surface with a facing of cast iron fused thereon and heated to a point where it will molecularly unite with the sheet steel.

5. The method of re-facing wrought metal structures comprising the flowing over a portion thereof of fused cast metal under suffi- 20 cient heat to fuse the surface of the wrought metal and integrate the cast metal therewith.

6. The method of re-facing wrought metal structures, comprising the displacement of 25 a piece of cast iron in proximity to the structure to be refaced, and simultaneous appli- cation of sufficient heat to the adjacent por- tions of the cast iron and wrought metal structure to fuse and integrate the same. 30

In testimony whereof I affix my signature at Detroit, Wayne county, Michigan, upon this 22nd day of March, A. D., 1916.

ALDEN L. PUTNAM.
